SAFETY RAZOR

Wilfred I. Ohmer, Dayton, Ohio

Application August 3, 1934, Serial No. 738,315

12 Claims. (Cl. 30—12)

This invention relates to improvements in safety razors, and has for its object to provide a reversible head, blade and guard.

It is an object of this invention to provide a safety razor having an arcuate head, a resilient blade, a resilient guard, a handle, and means for attaching the handle to the blade, the guard and the head so that the ends of the head, the guard and the blade will extend toward or away from the handle.

It is an object to provide a safety razor having an elongated, arcuate head with teeth on its arcuate edges, a blade to engage the concave side of the head, a handle engaging the convex side of the head, and means cooperating with the handle to flex the blade to hold it against the concave side of the head.

It is also an object of this invention to provide a razor consisting of a head, a blade, a handle and a pin passing through the blade and the head into the handle for holding the blade against the head.

It is particularly the object of this invention to provide a razor that may be used for shaving the arms, legs or any other arcuate convex part of the body, and may be also used for shaving under the arms.

These and other advantages will appear from the following description taken in connection with the drawings.

Referring to the drawings:

Figure 1 shows a razor having an arcuate head with the ends curved away from the handle.

Figure 2 shows the parts of the razor as shown in Figure 1 in positions for assemblage.

Figure 3 is a longitudinal section through the head, the blade and the guard, and the part of the handle adjacent the head.

Figure 4 is a section on the line 4—4 of Figure 3.

Figure 5 is a plan view of the head, the blade and the guard of the razor as shown in Figure 3.

Figure 6 is a section on the line 6—6 of Figure 1.

Figure 7 shows a razor composed of the same parts as the razor shown in Figure 1 but with the parts reversed, so as to form a razor with the ends of the head, the guard and the blade curved toward the handle.

Figure 8 is a view showing the various parts of the razor for assemblage purposes to form a razor such as that shown in Figure 7.

Figure 9 is a side elevation of a double-edged razor.

Figure 10 shows a razor composed of a head,

a blade, a reinforcing plate and a handle, the head, the blade, the reinforcing plate and a part of the handle being in section.

Figure 11 is a section on the line 11—11 of Figure 10.

Figure 12 is a view of the blade end of a razor showing a double-edged blade with the ends of the blade curved away from the handle.

Figure 13 is a side elevation of the razor shown in section in Figure 14.

Figure 14 is a section on the line 14—14 of Figure 13.

Figure 15 is a section through the stem and an arcuate rigid head thereon.

The razor shown in Figures 1, 2, 3, 7 and 8 is composed of five parts, an arcuate head, a flexible blade, a flexible guard, a handle and a screw or pin for holding the blade and the guard on the head. By using these five elements a razor may be formed in which the blade is curved away from the handle, as shown in Figures 1 and 3. From these same parts a razor may be formed in which the ends of the blade are curved toward the handle, as shown in Figures 7 and 8. This change is brought about by reversing the blade and the guard with relation to the head and the handle and the pin with relation to the head. The guard and the blade in each form have the same relative positions.

As shown in Figures 1, 2, 3, 7 and 8, the head 1 is oblong and longitudinally arcuate, and is provided, intermediate its ends, with an oblong irregularly shaped hole 2. Along one edge of the head and on the concave side thereof is a flange 3, which terminates in cam members 4. The blade 5 is flexible and has therein a hole of the same size and shape as the hole in the head. The guard 6 is oblong and has therein a hole corresponding in size and shape to the holes in the blade and the head. These holes are designated by the numeral 7, for the guard and blade.

In assembling the parts shown in Figure 3 the flange 3 and members or lugs 4 are at what may be called the back of the razor head. The guard 6 is assembled with the head with its rear edge placed against the flange 3 and the lugs 4, with the teeth on the other or front edge of the guard. The unsharpened edge of the blade 5 is also placed against the flange 3, so that its sharp edge will be adjacent the teeth 8 when the parts are assembled. The blade will be between the head and the guard, as indicated in Figure 8. Such is the arrangement in Figure 8 when the parts are assembled.

One edge of the guard is provided with teeth 55

- 8, such as usually found in guard members. For the purpose of holding the blade and the guard assembled and properly aligned on the head there is a pin or stem member 9 adapted to extend 5 through the holes 7 and engage a handle 12. In the present instance this stem or pin has oppositely disposed flat sides or faces 10 to engage the sides of the members in the elongated holes. The pin or stem is provided with a head 11.
- 10 In the arrangement shown in Figure 1 the handle is on the convex side of the head. The guard and blade are arranged one upon the other and placed upon the concave side of the head with the guard between the blade and the head.
- 15 The stem is extended through the members into the handle for holding the parts in the position shown in Figure 1.

In order to form the razor shown in Figure 7 the position of the assembled guard and blade upon the head is reversed. In this form the blade is between the guard and the head. The handle is attached to the head on the concave side thereof, while the head of the stem or pin engages the convex side of the head.

25 In Figure 9 there is shown a double-edged blade with a guard having teeth on oppositely disposed edges. In this form the head, the blade and the guard may be assembled to produce a razor in which the ends of the head, the blade 30 and the guard bend away from the handle, or these members may be assembled so their ends will bend toward the handle.

Instead of having a separate guard the head may serve as a guard, and for that purpose be 35 provided with teeth on opposite edges. Such a head is shown in Figure 11 and designated by the numeral 13. This head has on its opposite edges teeth 14 and a central hole 15. For use in connection with the head 13 there is a double-edged 40 blade 16 and a stem or screw 17, which has thereon a head 18 threaded into a handle 20. Cooperating with the head 18 for supporting and strengthening the blade there is provided a support spring 19. This spring may be welded to 45 the head or it may be formed as part of the stem head. The stem head may be in the form of an elongated, flexible plate substantially as wide and as long as the blade, or it may be rigid and arcuate, as shown in Figure 15.

50 In the form shown in Figures 13 and 14 there is shown a head 21, which has on one edge teeth 22 and on its other edge a flange 23. In this form of razor the head serves as a head and as a guard, and is preferably arcuate and receives on its concave side a blade 24 held to the head by means of a spring plate 25, suitably attached to or formed 55 as a head 26 for the screw or stem for holding the blade and head assembled on a handle 27.

In the form shown in Figure 9 the head is 60 designated by the numeral 28. This head is arcuate. Cooperating with this head is a double-edged blade 29 and a double-toothed guard 30, which has on opposite edges teeth 31. In this form the parts are held together by means of a pin which has a head 32 and extends into the handle 33. The pin is similar in all respects to the pins used in the other forms of razor.

It will be understood that I desire to comprehend within my invention such modifications as 70 come within the scope of my claims and my invention.

Having thus fully described my invention, what I claim as new and desire to secure by Letters Patent, is:

75 1. A razor consisting of an arcuate head, a

flexible blade and a flexible guard and means comprising a handle and a pin threaded into the handle to support and hold assembled the head, the blade and the guard the blade and guard being uniformly flexed against the head, said means being separate from the head, and guard and the blade but engaging each.

5

2. In a razor, an arcuate head, a blade and a guard assembled in definite relationship with each other, and means including a handle and a pin 10 threaded into the handle for attaching the blade and the guard to the head so that the razor may have a cutting edge that is either concave or convex with relation to the handle.

10

3. In a razor, an arcuate head, a flexible blade, 15 a flexible guard, a handle, and a removable pin to support the head on the handle and hold the blade and the guard assembled against the concave side of the head so that the ends of the head, the blade and the guard will curve toward 20 or away from the handle, said pin having means thereon engaging the blade when the handle is clamped on the convex side of the head.

20

4. In the razor, a head having integral guard means along its edges, a double-edged blade formed to fit the concave side of the head, a handle on the convex side of the head and removable means engaging the head and the handle to hold the blade on the head.

25

5. In a razor, an arcuate head having a hole 30 therein, a flexible blade and a flexible guard assembled in a definite relation to each other, the blade and the guard having holes therein, and means passing through the holes to flex the blade and the guard and hold them on the concave side 35 of the head with either the blade or the guard against the head.

35

6. In a razor, a handle, a flexible blade, and means to flex the blade and hold it on the handle 40 so that the convex side of the blade is nearest the handle, said means consisting of an oblong longitudinally arcuate rigid razor head and a stem adapted to be attached to the handle and having an elongated arcuate rigid head thereon cooperating with the razor head to flex and hold the 45 blade.

40

7. In a razor, an arcuate head having guard means along one edge, a blade formed to fit the concave side of the head, a handle on the convex side of the head, said head and blade having holes 50 therein, and a member engaging the head and the blade and extending through the holes into the handle to hold the blade on the handle, said member comprising a pin having a flexible head.

50

8. In a razor, a flexible blade, an arcuate rigid razor head, and means comprising a flexible element for flexing the blade against the concave side of the razor head and attaching the handle to the convex side of the razor head.

55

9. In a razor, an arcuate head, a blade, a guard, a handle, and means to support the head on the handle and hold the blade and the guard assembled against the concave side of the head so that the ends of the head, the blade, and the guard will curve toward or away from the handle, said means comprising a pin passing through the head, the blade and the guard and having a head in engagement with the arcuate head or in engagement with the blade, so that, when the handle 70 is clamped on the convex side of the arcuate head and the pin is engaging the blade, the guard is disposed between the arcuate head and the blade.

65

10. In a razor, an arcuate head having a hole 75 therein, a blade and a guard assembled in a definite relation to each other, the blade and the

75

guard having holes therein, and means passing through the holes to clamp the blade on the guard and hold them on the concave side of the head with either the blade or the guard against the head, said means consisting of a handle and a pin 5 engaging the handle and having a head to engage the arcuate head or the assembled blade or guard, so that, when the handle is clamped on the convex side of the arcuate head and the pin is engaged the blade, the guard is disposed between the arcuate head and the blade.

10 gaging the blade, the guard is disposed between the arcuate head and the blade.

11. In a razor, an arcuate head having a hole 15 therein, a blade and a guard assembled in a definite relation to each other, the blade and the guard having holes therein, and means passing through the holes to clamp the blade and the

guard and hold them on the concave side of the head with either the blade or guard against the head, said means consisting of a handle and a pin threaded into the handle and having a head to engage the arcuate head or the assembled blade or guard so that, when the handle is clamped on the convex side of the arcuate head and the pin is engaging the blade, the guard is disposed between the arcuate head and the blade.

12. In a razor, a handle, a flexible blade, an arcuate rigid razor head having guard means thereon, and means comprising a flexible element for flexing the blade against the concave side of the razor head and attaching the handle to the convex side of the razor head.

15 WILFRED I. OHMER.
